AUTOMATIC FIREARM

Marc Birkigt, Bois-Colombes, France

Application April 16, 1938, Serial No. 202,545
In Belgium February 11, 1938

4 Claims. (Cl. 42—3)

The present invention relates to automatic firearms and in particular, but not exclusively, light guns for use on aircrafts.

In guns of the type with which the present invention is concerned, the tube of the arm is provided at the rear with a movable breech system adapted to recoil when a shot is fired, against the action of a counter spring, and to be locked, at least partly, when brought back into firing position. Usually, this movable breech system includes a breech block proper adapted to close the tube and hold the cartridge firmly in the chamber thereof, when locked in said firing position, and a sliding part, carrying the firing pin, normally locked to the breech block when the latter is not locked in firing position and adapted to further move in the forward direction with respect to said breech block after the latter has been locked, under the effect of the counter spring and also of inertia, whereby the firing pin is caused to strike the cartridge.

In guns of this type, when the gun is not to fire, the whole of the movable breech system is locked in its rear position, corresponding to the beginning of the return stroke thereof.

The object of the present invention is to provide a breech mechanism of the type above referred to which is better adapted to meet the requirements of practice than mechanisms used up to the present time for the same purpose.

According to the essential feature of the present invention, the sear or equivalent part adapted to hold the movable breech system in the rear position thereof, so as to stop the working of the firearm and to control the action thereof, cooperates with the locking member, carried by the movable breech system, which locks said breech system in the forward or firing position thereof.

Other features of the present invention will result from the following detailed description of a specific embodiment thereof.

A preferred embodiment of the present invention will be hereinafter described, with reference to the accompanying drawing, given merely by way of example, and in which:

Fig. 1 is an elevational view, partly in axial vertical section, showing the breech mechanism of an automatic firearm made according to the present invention;

Fig. 2 is a similar view of the same mechanism, with the parts occupying different relative positions, corresponding to another time of operation;

Fig. 3 is a sectional view on the line III—III of Fig. 1;

Fig. 4 is a vertical section on the line IV—IV of Fig. 1;

Fig. 5 is a vertical section on the line V—V of Fig. 2.

In the embodiment of my invention, illustrated by the drawing, at the rear of the barrel or tube 1, the structure of which has no bearing upon the present invention, a breech casing 2 is rigidly fixed. This casing 2 acts as a guide for the movable breech structure which will be described later. Casing 2 is provided with a cartridge feeding slot 3 and a diametrically opposed slot 4 for the ejection of the cartridge cases.

The movable breech structure which is slidable in said casing 2 is urged forwardly by a counter-spring 5, toward the position in which it closes the rear end of the barrel or tube.

In the embodiment described by way of example, this movable breech structure is made of two parts slideable relatively to each other in the direction of the general sliding displacement of the whole.

One of these two parts is constituted by the breech block proper 6, that is to say the part which forces and wedges the cartridges into the chamber of the barrel or tube of the gun.

The other part 8, movable longitudinally with respect to said breech block, carries the firing pin 9.

The breech block 6 carries, pivotally mounted thereon, at the lower part, a pawl 7 for the locking of said breech block, and said pawl is made of a material as hard as possible, for instance case-hardened steel.

This pawl is adapted to oscillate between two extreme positions, which will be called herein-after the upper position (Fig. 2) and the lower position (Fig. 1).

When pawl 7 is in the upper position, it interconnects the breech block 6 with the other breech element 8, this position being that occupied by the parts as long as the breech block is at the rear of its firing position.

On the contrary, when pawl 7 is in its lower position, it locks the breech block with respect to casing 2 as soon as said breech block reaches its firing position, so that said block is stopped in said position. The other breech element, to which 8 carries striker 9, is then free to move alone toward the cartridge, this supplementary displacement being made possible by the provision of an elongated passage 6' in the breech block 6 and being produced by the action of the counter spring 5. This movement corresponds to the percussion of the cartridge which, at this time is

being securely held in the tube chamber by the breech block 6.

I further provide means for imparting a recoil movement to breech element 8 after each shot 5 has been fired. In the example shown by the drawing, the means in question consist of a cylinder and piston system the movable element 11 of which is rigid with a push piece 12 adapted to act on said element 8.

10 This relative movement of element 8 with respect to the breech block 6 brings a recess provided in the lower part of element 8 above the end of pawl 8, so that when, under the effect of the reaction of the powder gases, pawl 13 tends 15 to pivot upwardly (owing to the upward component produced by inclined surface 13), said pawl can engage into said recess, thus unlocking the whole of the breech structure from the breech casing, and permitting the rearward movement of said breech structure, the elements 20 6 and 8 of which are now interlocked by pawl 7 engaged in the above mentioned recess of element 8.

In order to prevent the gun from firing, the 25 whole of the breech structure is held in its rear position by the following means:

A sear or catch 14 carried by the breech casing is arranged normally to project into the inside of said casing so as to engage with the breech 30 structure and to stop it at the beginning of its return stroke. This catch is normally urged toward this stopping position by a spring push-piece 15 slidably transversely in the breech casing. Control means for releasing the breech 35 structure from this locking action are constituted, in the example disclosed by the drawing, by a stirrup 16 operative by means of a cable 17. When said cable is pulled, the gun starts firing, and as soon as the cable is released, the 40 firing stops.

According to the essential feature of the present invention, the nose 14' of this sear or catch 14, instead of cooperating directly with the breech block, as it was the case up to the present 45 time, engages into a notch, or the like, 18 provided in pawl 7, preferably in the rear middle portion thereof.

The chief advantage of this arrangement is that the fire control system is particularly strong 50 because the stopping of the breech structure in the rear position is ensured by the cooperation of two elements (7 and 14) both of which are made of particularly hard metal (since catch 14 is generally made, like pawl 7, of case hardened steel).

Furthermore, when notch 18 finally becomes 55 deteriorated by wear and tear, it suffices to change the locking pawl 7, instead of having to change the whole of the breech block.

60 In a general manner, while I have, in the above description, disclosed what I deem to be practical and efficient embodiments of the present invention, it should be well understood that I do not wish to be limited thereto as there might 65 be changes made in the arrangement, disposition, and form of the parts without departing from the principle of the present invention as comprehended within the scope of the accompanying claims.

70 What I claim is:

1. An automatic firearm which comprises, in combination, a tube, a breech structure movable with a longitudinal reciprocating motion

in line with said tube at the rear thereof, a stationary guide for said breech structure rigid with said tube, a pawl pivoted to said breech structure adapted to cooperate with said guide for locking said breech structure in the front position thereof with respect to said tube, and locking means carried by said stationary guide adapted to cooperate with said locking pawl for holding said breech structure temporarily in rear position in said guide. 10

2. An automatic firearm which comprises, in combination, a tube, a breech structure movable with a longitudinal reciprocating motion in line with said tube at the rear thereof, a stationary casing with said tube for guiding said breech structure, said breech structure including a breech block and a firing pin carrier movable to a limited extent with respect to said breech block, a pawl pivoted to said breech block adapted to cooperate with said casing for locking said breech block in the front position thereof with respect to said tube, said pawl being further adapted to lock said breech block with said firing pin carrier when said breech block is located behind said front position, and locking 15 means carried by said stationary casing adapted to cooperate with said locking pawl for locking said breech structure temporarily in rear position with respect to said stationary casing. 20

3. An automatic firearm which comprises, in combination, a tube, a breech structure movable with a longitudinal reciprocating motion in line with said tube at the rear thereof, a stationary casing rigid with said tube for guiding said breech structure, said breech structure including a breech block and a firing pin carrier movable to a limited extent with respect to said breech block, a pawl pivoted at its front part to said breech block adapted to cooperate alternately with said casing when said breech block 35 is in the front position for locking it in said position, and with said firing pin carrier for locking the latter with said breech block when said breech block is behind said front position, a pawl movably carried by said stationary casing 40 adapted to cooperate with said first mentioned pawl for locking said breech structure temporarily in rear position with respect to said stationary casing, and means for controlling said second mentioned pawl. 45

4. An automatic firearm which comprises, in combination, a tube, a breech structure movable with a longitudinal reciprocating motion in line with said tube at the rear thereof, a stationary casing rigid with said tube for guiding said breech structure, said breech structure including a breech block and a firing pin carrier movable to a limited extent with respect to said breech block, a locking pawl pivoted at its front end to said breech block adapted to cooperate alternately with said casing when said breech block is in the front position for locking it in said position, and with said firing pin carrier for locking the latter with respect to said breech block when said breech block is at the rear of said front position, said pawl being provided with a notch in its intermediate portion, a catch movably carried by said stationary casing so as to be able to engage into said notch for locking said breech structure temporarily in rear position with respect to said casing, and means for controlling said catch. 55
